IMPACT CRUSHER

Charles A. Adams, Wurtsboro, N. Y.

Application December 17, 1953, Serial No. 398,775

7 Claims. (Cl. 241—275)

My invention relates to a crusher and more particularly to an impact type crusher for crushing stone, ores or other crushable material.

My improved impact crusher is of the type wherein crushable material is fed to the center of a rotating impeller which throws the crushable material out centrifugally against impact surfaces which are substantially normal to the trajectory of the impelled material.

It is an object of the invention to provide an improved impact crusher wherein an impact surface is substantially normal in all directions to the trajectory of an impelled particle.

It is another object to provide an impact crusher having a small plurality of impact surfaces all points of which are substantially normal to the trajectories of particles discharged by the impeller.

Another object is to provide an impact crusher having only a small number of surface parts subjected to normal wear.

It is another object to provide an impact crusher having impeller means and impact means relatively adjustable, so as to present new wear surfaces in case of excessive wear.

Further object is to provide an impact crusher having a centrifugal type impeller and a small plurality of impact surfaces adjustable to compensate for wear.

It is another object to provide an impact crusher arranged for a relatively free discharge of crushed material and the production of a highly cubical product with a relatively small amount of extreme fines.

Other objects and various features of novelty and invention will be hereinafter pointed out or will become apparent to those skilled in the art.

In the drawings which show, for illustrative purposes only, a preferred form of the invention—

Fig. 1 is a top plan view in partial section of an impact crusher illustrative of the invention;

Fig. 2 is a vertical sectional view taken substantially in the plane of the line 2—2 of Fig. 1;

Fig. 3 is a detail top plan view of the centrifugal impeller and impact plates, the view being similar to Fig. 1, with the top removed to illustrate interior construction;

Fig. 4 is an enlarged detail view of means for adjustably holding an impact plate in a crusher housing;

Fig. 5 is a view similar to Fig. 4, but illustrating parts in different positions;

Fig. 6 is a top plan view of a modification; and

Fig. 7 is a fragmentary sectional view substantially on the line 7—7 of Fig. 6.

In the preferred form of the invention illustrated, I provide a main frame or housing 5 which may be mounted upon foundation pillars or other type of foundation 6, as will be understood. The housing 5 supports beams 7—8 for supporting a central shaft housing 9. This housing carries the main impeller shaft 10 on

bearings such as antifriction bearings 11—11, mounted in the shaft housing 9.

Drive means, such as a motor 12, is supported preferably on the outside of the housing 5, and drive means, such as a belt 13, serves to drive the impeller shaft 10 from the motor. The impeller 14' shown in Fig. 1 may be of conventional form or may embody substantially the same parts as those just described.

The impeller shaft 10 carries an impeller 14, which is rotated thereby. The impeller preferably comprises bottom plates 15, which may extend to opposite sides of the central shaft 10, so as to, in effect, form a double impeller. Each bottom plate 15 is preferably of a relatively hard abrasive-resistant material so as to reduce wear due to crushable material being thrown outwardly from the impeller. The impeller also includes generally vertical side plates 16 also formed of hard abrasive-resistant material to reduce wear due to the crushable material thrown out. The plates 15—16 are preferably removable and may be secured to the main impeller housing 17 as by means of bolts 18, as will be understood.

Crushable material is fed to the impeller 14 substantially at the center, as by means of an inlet pipe or conduit 19 extending down vertically through the cover 19', secured on the housing 5. Thus, crushable material fed into the inlet conduit 19 through any suitable type of hopper as shown, will drop down onto the impeller substantially to the center, and since the impeller is rotating at relatively high speed counterclockwise as viewed from the top, the crushable material will be thrown out centrifugally along the vertical walls 16, while resting and sliding, of course, on the bottom plates 15.

Any particles leaving the impeller will have a velocity and direction which may be resolved into a tangential component and a generally radial component; that is to say, any particle leaving the impeller will tend to fly off in a tangential direction, but since it has a very high radial velocity due to the centrifugal action of the impeller, it will also tend to fly off in a radial direction. The trajectory of the particle will be the resultant of all of the directional components.

As shown particularly in Fig. 3, a material particle 20 is shown at the point of discharge from the impeller. The particle 20 will have a tangential directional component 21 due to the rotation of the impeller, and will have a radial directional component 22 due to the centrifugal action of the impeller. In the form shown, we have assumed the component 21 to be the actual measure of tangential velocity and direction, and the component 22 we have assumed to be about 90 percent of the tangential velocity, it being assumed that the tangential and the radial velocities would be theoretically equal. Due to the frictional resistance, the radial velocity, it has been assumed, would be only about 90 percent of the tangential velocity. The resultant of the component velocities 21 and 22 is represented by the line 23, and the actual velocity and direction of any material particle may be represented by the line 23.

Since the particle 20 as shown in Fig. 3 is any particle, it will be clear that if trajectories be laid out for a part of the revolution of the impeller, trajectories 23 as shown in Fig. 3 will be obtained. It will also be observed that an arc drawn tangent to all of the trajectory lines 23—23 will be a circle of diameter less than the diameter of the circle generated by the impeller at the point of discharge.

The impact plates, such as 25, have impact surfaces 26 which are substantially normal in all directions to the trajectories of particles discharged by the impeller; therefore, the impact surface 26 at every point is substantially normal to one of the trajectory lines 23, and, therefore,

the impact surface 26 is an involute about the circle 27 which, as stated, is of a diameter less than the diameter of a circle generated by the point of discharge of particles from the impeller. While a single impact surface 26, in the form of an involute about the circle 27, might be formed in a single case or housing, the design would be wholly impractical and, therefore, it is desirable to provide a small plurality of different impact surfaces 26, 26¹, 26², etc. on impact plates 25. In the form shown, we have provided four impact surfaces, and the design is quite satisfactory.

It will be seen that the forward tip 28 of each impact surface, in effect, overlaps the rear end 29 of the next succeeding impact plate, so that every particle of crushable material discharged by the impeller will be almost certain to strike a surface substantially normal to the trajectory of each particle discharged by the impeller. The impact plates 25 in effect form a housing, but the outer housing casing 5 is provided for completely enclosing all of the impact plates and confining the crushed material. These plates are preferably supported in the housing by means of a circumferential angle bracket 30, upon which the plates may rest, as shown partly in Fig. 5. Within the housing, I also preferably provide the framework or abutment means 31 for the forward or free end of each impact plate, as will be particularly clear in Fig. 3. The impact plates may have a rearwardly extending longitudinal flange 32, having an aperture 33 therein for receiving a hook bolt 34 passing through an opening in the housing 5, which may be secured as by means of a nut 35. Thus the impact plates 25 may be drawn up against the housing 5 at the rear end and against the abutment means 31 at the forward end, and very securely held in place. These impact plates are preferably formed, at the impact surface at least, of impact- and abrasion-resistant material, preferably of such a nature that the surface hardens by the impact of particles of crushable material.

I have provided means for adjusting the relative positions of the impact plates and impeller, so that, in case of substantial wear or grooving of the impact plates, there may be a relative change of position. In the form shown, I may provide spacer blocks 36, which may be positioned between the angle iron supporting bracket 30 and the rear end 29 of each impact plate, and also between the forward end of each impact plate and a shelf 37 on the abutment or strut work 31. When the impact plates are made adjustable as described, I preferably provide a slot 40 in the housing 5 as indicated in Fig. 4, so that the hook bolt 34 may be adjusted up and down and always rigidly hold the impact plates in place in the housing. Thus, if the impact plates should become worn, for example if a groove should form, the plates may be adjusted upwardly so as to present a new surface to the particles thrown out by the impeller; thus, the life of the rather expensive impact plates may be substantially prolonged.

It will be observed that the extreme forward ends 28 of the impact plates are subject to impact and possibly glancing blows of crushable particles. The wear on such points will be substantially greater than on other surfaces, and it may be desirable to move such forward ends 28 closer to the impeller so as to present better surfaces to the crushable particles. In order to permit the forward end of the impact plate to be adjusted, I may arrange to loosen the nuts 35 and swing the forward ends 28 outwardly, and insert a shim or distance block 41 so as to adjust outwardly and position each plate without, however, very substantially altering the relative positions of the impact plates and the impeller. Even after such slight adjustment, the impact surfaces will be substantially normal in all directions to the trajectory of particles impelled by the impeller.

In the modification shown in Figs. 6 and 7, the impact plates are supported slightly differently and are reversible end for end. Each impact surface is a true arc but differs

in form so slightly from an involute that for all practical and functional purposes the surface is normal to the trajectory of the particles discharged by the impeller.

In this modified form the casing 5 has struts or supports 45—46 welded thereto, and angle irons 47—48 are welded to these struts. A shelf bracket 49 rests on the strut 45 and is bolted to the angle 47. The impact plate 50 is supported on the bracket 49.

The impact plate 50 has the impact surface 51 in the form of a true arc but, as stated, the arc differs so little from the true involute (see dotted line showing) that for all practical and functional purposes the surface is normal to the trajectory of the particles discharged by the impeller. The back of the impact plate has flat bosses 52 which seat flat on the flat surfaces of the angles 47—48. The plate has an integral eye 53 at the rear to receive the hook bolt 54, which is secured to the casing and holds the impact plate rigidly in place.

It will be seen that the impact plate is fully symmetrical and therefore may be turned end for end to distribute the wear and prolong the life of the plate. The true arc is also easier to machine than the true involute and therefore the arcuate impact plate is cheaper to manufacture.

It will be seen that the impact plates have substantially vertical surfaces so that, as indicated, the impact surfaces are substantially normal in all directions to the trajectory of all particles thrown out by the impeller. With the impact plates substantially vertical, the crushed particle will readily fall downward, and there will be no glancing blows or ricocheting particles to bang about in the crusher, and there will be very few impacts of the particles against the impact plates or against each other; that is to say, each particle will strike the impact plate and the crushed particles will fall straight down and all of the particles will have fallen down before the impeller turns around so as to discharge another particle onto that particular part of the impact plate. Thus, with each particle striking the impact plate only once, and not being struck by other particles, the crushing will be excellent and the production of substantial quantities of extreme fines will be reduced to a minimum. Generally speaking, the higher the speed of the impeller the finer will be the crush.

It will be seen that my crusher is formed of relatively few parts, all of sturdy construction and not likely to get out of order. The impact plates are duplicates of each other, and may be securely held in place in the crusher housing, and may be adjusted when required. The wear surfaces on the impeller may be readily renewed when worn out. All of the moving parts, such as the impeller bearings, etc., may be completely housed so as to be shielded from dust and other foreign matter.

The crusher is simple to operate, and will effectively crush crushable material to the desired extent without the production of excessive extreme fines.

While I have described one form of the invention in detail, it will be understood that modifications may be made within the scope of the invention as defined in the following claims.

I claim:

1. In an impact crusher, a housing, a centrifugal impeller in said housing to throw crushable material outwardly, an impact plate in said housing and having an impact surface substantially normal to the trajectory of a particle impelled by said impeller, means for adjusting said impact plate in a direction axially of the axis of rotation of said impeller and means for drawing said impact plate generally radially outwardly in said housing.
2. In an impact crusher, a housing, a centrifugal impeller rotatably mounted in said housing for impelling crushable material outwardly, an impact plate in said housing, abutment means for sustaining said impact plate in a radial direction, means for drawing outwardly on said impact plate to urge the latter into seating contact with

said abutment means, said impact plate having flat abutment surfaces to seat on said abutment means.

3. In an impact crusher, a housing, a centrifugal impeller rotatably mounted in said housing for impelling crushable material outwardly, an impact plate in said housing, abutment means for sustaining said impact plate in a generally radial direction, said impact plate having a rearward projection with a transverse hole therein, and means engaging in said hole for urging said impact plate generally radially outwardly into firm engagement with said abutment means.

4. In an impact crusher, a housing, a centrifugal impeller mounted for rotation in said housing, an inlet to said impeller, a plurality of impact plates in said housing, each said impact plate comprising a generally arc shaped plate member, said generally arc shaped plate member being tipped in said housing so as to position one end adjacent said housing and the other end adjacent said impeller, each said impact plate member when in said position having its front impact surface formed and positioned substantially normal to the trajectories of particles thrown centrifugally against it by said impeller, abutment means formed on the inside of said housing to abut said rear side of said generally arc shaped plate means to sustain the same in the position aforesaid, and

15 means for drawing said arc shaped impact plate members on to said abutment means.

5. In the combination defined in claim 4, the end of said generally arc shaped impact plate which is adjacent said housing being in contact with the inside of said housing.

6. In the combination defined in claim 4, said generally arcuate impact plate being substantially symmetrical and interchangeable end for end on its said abutment means.

7. In the combination defined in claim 4, said abutment means in said housing serving to hold both rear ends of said generally arc shaped impact plate away from the inside of said housing.
